KNITTING MACHINE

Fritz Lambach, Tenafly, N. J.

Application November 2, 1944, Serial No. 561,529

25 Claims. (Cl. 66—1)

1

My invention relates to knitting machines, and more particularly to means for ascertaining a properly timed relationship between the operations of the various mechanisms of a knitting machine.

In knitting machines now ordinarily made, the operations of the various mechanisms—for example the yarn feeding elements, the needles, the sinkers, the knockover bits, the fabric take-up device, and other knitting implements the knitting machine might have—are controlled by cams, pattern wheels or the like adjustably mounted on a shaft or shafts driven by the main drive. In order to manufacture a certain fabric of a certain quality with certain yarns by a knitting machine, it is necessary that the operations of the various mechanisms of the knitting machine are precisely timed relative to each other. A different timing of the operations of the various mechanisms, however, becomes necessary, if on the same knitting machine a fabric of a different quality shall be knitted, or if different yarns are to be used for the knitting of a fabric. Therefore, the cams, pattern wheels or the like actuating the various mechanisms of a knitting machine must be precisely set or reset in predetermined positions relative to each other on the shaft or shafts of the knitting machine.

In many knitting machines a great number of cams are arranged next to each other on a so-called main cam shaft; such an arrangement renders difficult the access to cams arranged in the center of the main cam shaft for a setting thereof. Furthermore, in many knitting machines, a number of cams rotate at speeds different from the speed of the majority of cams of the knitting machine, whereby the setting of the cams in the proper position relative to each other is complicated. Moreover, many cams of knitting machines have a contour which only slightly deviates from a round circumference, so that the rise or dwell of such a cam, and consequently its position relative to the shaft and/or the remaining cams of the knitting machine, can hardly be recognized. All these features render the setting and resetting of cams, pattern wheels or the like on a shaft or shafts of a knitting machine a very difficult and cumbersome operation.

The difficulties for a proper operation of a knitting machine outlined above are enhanced by hitherto customary insufficient and unsatisfactory methods and means for setting and resetting the cams on a shaft or shafts of knitting machines. For example, according to a hitherto customary practice, the operator of a knitting

2

machine scribes a line on each cam to be set or reset, in a certain relation to the contour of the cam according to instructions given to him. Obviously, the scribing of the line depends entirely on the skill of the operator, and it may readily occur, that the line is not in the exact position relative to the contour of the cam. Furthermore, it is extremely difficult to scribe a line accurately in relation to the contour of a rather round cam.

Moreover, it is extremely unlikely, that the operator scribes the line on exactly the same position relative to the contour of the cam each time when the cam is to be set or reset. After the time consuming scribing of such a line on each cam to be set or reset, the cam loosely arranged on a shaft is rotated on the shaft, until the scribed line is opposite a pointer held in a certain position, whereupon the cam is secured to the shaft in the thus set position. As will be apparent from the foregoing, the setting of cams on a knitting machine by scribing of lines or by any other means depending on the skill of the operator for the observation of the contour or a point of the contour of the cam relative to a fixed point provides only for a rather coarse adjustment of the cams and does not assure repeated identical settings of the cams, and the best knitting machines with cams thus set can hardly be operated with satisfactory results.

30 An object of the present invention is to provide a knitting machine, wherein the operation of the various mechanism may be precisely timed relative to each other.

35 A further object of the present invention is to provide a knitting machine, wherein the cams or the like may be readily set in a short time in accurate positions relative to each other for the timing of the operations of the various mechanisms.

40 Another object of the present invention is to provide a knitting machine, the cams of which may be repeatedly set and reset in identical positions relative to each other.

45 A further object of the present invention is to provide a knitting machine, the cams of which permit a ready attachment of a movable gauge member of a cam position indicator, which may be used either for an accurate setting of the cams in predetermined positions or for an indication 50 of the set position of the cams on the shaft or shafts of the knitting machine for a ready check up of the operations of the mechanisms of the machine.

Still another object of the present invention is 55 to provide a cam position indicator which may

be readily attached to cams of a knitting machine irrespective of the location of the cams in the knitting machine.

My invention consists in certain novel features of construction of my improvements as will be hereinafter fully described.

Above mentioned objects and advantages of the invention as well as other objects and advantages will be more fully disclosed in the following specification reference being had to the accompanying drawings forming part of this specification, wherein:

Fig. 1 is a diagrammatical view of parts of a knitting machine illustrating the attachment of cam position indicators to cams thereof,

Fig. 2 is a sectional view taken on line 2—2 of Fig. 1, in enlarged scale,

Fig. 3 is a side elevational view of the stationary gauge member of the cam position indicator shown in Fig. 2,

Fig. 4 is a back perspective view of the movable gauge member of the cam position indicator shown in Fig. 2,

Fig. 5 is an elevational view, partly in section, of a different embodiment of a cam position indicator attached to a cam of a knitting machine, and

Fig. 6 is an elevational view of a partly finished blank used for the manufacture of the cam shown in Fig. 2.

With reference to Fig. 1 diagrammatically illustrating only those parts of a warp knitting machine which are necessary for an understanding of the invention, it is understood that the arrangements and proportions shown in said figure are chosen for a better explanation of the invention, and that, in practice, the arrangements and proportions of these parts may differ from that shown in said figure without departing from the spirit and scope of the invention. In said Fig. 1, 10 indicates a main cam shaft journaled in suitable bearings of a frame generally indicated by 12. The main cam shaft 10 driven by a drive (not shown) carries a plurality of cams, for example the needle bar cams 14n, the sinker bar cams 14s, the guide bar cam 14g, the presser cam 14p, the take-up cam 14t, actuating through the medium of followers 16n, 16s, 16g, 16p, 16t various mechanisms of the warp knitting machine. A gear 18 keyed to the main cam shaft 10 is in mesh with a gear 20 keyed to a shaft 22 journaled in suitable bearings of the frame 12. A worm 24 keyed to said shaft 22 is in mesh with a worm gear 26 secured to a shaft 28 rotatably mounted in bearings of the frame 12. Said shaft 28 carries pattern wheels 30 (only one being shown in Fig. 1) for the actuation of the guide bars in a manner known per se. Owing to the worm and worm gear arrangement, the pattern wheels 30 rotate at a slower speed than the cams 14n, 14s . . . of the knitting machine.

According to the invention, each of the cams 14n, 14s . . . to be set in a predetermined position on the main cam shaft 10 is provided at one of its side surfaces with spaced engaging means or engaging holes 32 (see Figs. 2 and 6) which are arranged in a predetermined position relative to the contour of the cam. Likewise, each pattern wheel 30 to be set on the shaft 28 has on one of its side surfaces spaced engaging holes 32 (see Fig. 1) which are arranged in a predetermined position relative to the contour of the pattern wheel. When it is desired to set or reset the cams and pattern wheels of the knitting machine in a predetermined position relative to each other, so as to

obtain a predetermined timed operation of the various mechanisms of the knitting machine, relative to each other, said engaging means 32 or 132 may be used for a temporary connection of a cam position indicator to be described hereinafter.

In Fig. 2, 36 generally indicates an embodiment of a cam position indicator, which for example may be used for the setting of the cams 14s, 14t, 14n, 14g, 14p on the main cam shaft 10. Said cam position indicator 36 comprises a movable gauge member 38 made of a flat piece of material and a stationary gauge member 40 in the shape of a pointer. The movable gauge member or plate 38 is provided with a graduated scale 42 for cooperation with the pointer 40. Furthermore, the movable gauge member or plate 38 has a forked end portion provided with complementary spaced engaging means or engaging pins 44 extending from its back-side as best shown in Fig. 4. Said complementary spaced engaging pins may be inserted into the spaced engaging holes 32 at a side surface of a cam, so that, upon an attachment of the movable gauge member 38, the latter is positively coupled with the cam and held in a predetermined position relative to the contour of the cam as shown in Fig. 2. As will be apparent from above, the movable gauge member 38 may be readily attached to the side surface of any of the cams arranged next to each other on the main cam shaft irrespective of the location of the cam on the shaft; the portion of the movable gauge member 38 engaging the side surface of a cam is flat and its forked end is of such a shape, that it renders possible a movement of the movable gauge member into its coupling position with a cam in a direction at an angle to the longitudinal axis of the shaft 10 carrying the cam without interference with said shaft. The stationary gauge member or pointer 40 may be held in a predetermined position relative to the shaft 10 carrying the cam to be set thereon by supporting means generally indicated by 46 in Figs. 2 and 3. Said supporting means 46 comprise a holder 48 slidably and adjustably mounted on clamping means 50, which may be secured to a fixed part of the knitting machine by means of a set screw 52. For example, the clamping means 50 may be secured to a shaft 54 carrying a follower of one of the cam mechanisms or to a rod placed on the frame of the machine or to a stationary part of the frame of the machine. The holder 48 slidably in vertical direction may be held in its adjusted position by means of screws 56. The pointer 40 slidably and adjustably in a horizontal position on the holder 48 may be held in an adjusted position by means of screws 58. Above described cam position indicator 36 may be used in conjunction with the cams 14s, 14t . . . of the warp knitting machine in the following manner:

A table is given to the operator of the machine, indicating the position of the pointer 40 relative to the shaft 10 and indicating a certain value for each cam to be set for a certain operation of the knitting machine. For example, such a table may indicate that the stationary gauge member or pointer 40 is to be held in such a position by the supporting means 46, that the point of the pointer is in a horizontal plane with the center of shaft 10 as shown in Fig. 2, and such a table may indicate the value 0 for the sinker bar cams 14s, the value +3 for the needle bar cams 14n, the value -7 for the take-up cam 14t, and other values for other cams. The operator attaches

the supporting means 46 of the stationary gauge member 40 to a fixed part of the knitting machine, for example to the shaft 54 opposite the cam to be set, for example a sinker bar cam 14s, and adjusts the pointer 40 in the proper position relative to the shaft 10 as shown in Fig. 2. Furthermore, the movable gauge member 38 is attached to the sinker bar cam 14s, loosened on the shaft 10. Thereupon, the sinker bar cam 14s is displaced relative to the shaft 10 by rotating the cam on the shaft held in its position, until the pointer 40 co-operating with the graduated scale of the movable gauge member 38 indicates the value 0 as shown in Fig. 2. Now, the sinker bar cam 14s is in the position to be set and may be tightened on the shaft 10 by means of a set screw 60 engaged with registering holes 61 and 63 of a split portion of the cam; the threaded end of said set screw is threaded into the hole 63. After the setting of the first cam, the next cam may be set in similar manner. The shaft 10 remains in its position and the cam position indicator 36 is attached to the next cam, for example the take-up cam 14t. This take-up cam 14t is tightened on the shaft, when the cooperating gauge members 40, 42 of the cam position indicator indicate the value -7. Obviously, when each cam of the knitting machine is set in the described manner, according to the values on the table, the cams will be in accurate predetermined positions relative to each other on the knitting machine, so that an accurate timed operation of the various mechanisms of the knitting machine relative to each other is assured. Now, if for a different operation of the knitting machine, for example for the manufacture of a fabric of different quality, some of the cams have to be set in a different position while some of the cams remain in the same position according to a table, given to the operator, the operator attaches the cam position indicator 36 to a cam remaining in its position on the shaft. This particular cam is not loosened, and the operator rotates the shaft by hand, until the cam position indicator indicates the value pertaining to the setting position of said particular cam. Now a cam to be set in a different position for such a different operation of the knitting machine is loosened and the cam position indicator 36 is attached to such a cam, which is rotated relative to the shaft, until the cam position indicator indicates the value pertaining to said particular cam for the different operation of the knitting machine. All cams to be set in different positions may be set by means of the cam position indicator 36 in a similar manner.

As will be readily understood, the cams of the knitting machine may be reset by the use of the cam position indicator 36 into exactly the same position relative to each other as they had for the first operation mentioned above, if such a first operation is again desired.

According to above description of the operation of the cam position indicator, it is assumed that the same cam position indicator is used for all cams on the shaft 10. In such a case, of course, the spaced engaging holes 32 of all cams are in the same position relative to the shaft 10, when the cooperating gauge members indicate a certain value, for example the value 0. If desired, however, different cam position indicators may be used for different types of cams. For example a first cam position indicator may be used for the setting of the set of sinker bar cams 14s, a second cam position indicator may be used

for the setting of the needle bar cams 14n, etc. In such a case, the spaced engaging holes of all cams of a set of cams are in the same position relative to the shaft 10, when the cam position indicator indicates a certain value, but the spaced engaging holes of the cams of one set of cams may be in a different position relative to the shaft than the spaced engaging holes of the cams of another set of cams, when the cam position indicators indicate a certain value.

If the cam position indicator is to be used only for a certain knitting machine, the adjustable supporting means 46 shown in Fig. 2 may be replaced by a non-adjustable supporting means, so that the pointer 40 is automatically brought into the proper position relative to the shaft 10, when the supporting means 46 is attached to a fixed part of the knitting machine. Furthermore, the movable gauge member 38 must not necessarily be in the shape of a plate, it could be in any other suitable shape, if desired. Preferably, however, the portion of the movable gauge member carrying the complementary engaging pins is flat and/or of such a shape that it permits a movement of the movable gauge member into its coupling position with a cam in a sidewise direction substantially parallel to the side surface of the cam. Moreover, the movable gauge member could be in the shape of a pointer or could carry a pointer instead of a graduated scale; in such a case, of course, the stationary gauge member would carry the graduated scale.

According to Fig. 1, a somewhat different embodiment of a cam position indicator 136 is used for the setting of the pattern wheels 30. Said cam position indicator 136 comprises a movable gauge member 138 with spaced complementary engaging pins substantially corresponding to the movable gauge member 38 of the cam position indicator 36, described above. The stationary gauge member, however, comprises a supporting means 146 in the shape of a bar having a hook-like portion 150 for engagement with the shaft 28 carrying the pattern wheels 30. A stationary gauge member or pointer 140 is adjustably mounted on said supporting means 146. In use, the movable gauge member 138 is attached to the side surface of a pattern wheel 30 by the insertion of its engaging pins into the engaging holes 132, and the supporting means 146 is engaged with the shaft 28 while its free end rests on a stationary part of the frame 12 of the machine. The cam position indicator 136, the pointer 140 of which cooperates with the graduated scale 142, may be used in the same manner as the cam position indicator 36 described above.

Fig. 5 illustrates a different embodiment of a cam position indicator, generally indicated by 236, which may be used in conjunction with cams or pattern wheels or the like of a knitting machine. According to Fig. 5, the movable gauge member 238 of the cam position indicator is in the shape of a bar having spaced engaging pins for engagement with spaced engaging holes 232 of a cam 214, adjustably mounted on a shaft 210 of a knitting machine. The stationary gauge member of the cam position indicator shown in Fig. 6 comprises a supporting means 250, which may be attached to a stationary or fixed part of the knitting machine by a set screw 252 and has a recess 262 for the reception of one or the other of a series of gauge blocks 240 of different size. When the cam position indicator according to Fig. 5 is used, the support 250 is held in a predetermined position relative to the shaft 210,

and the gauge block 240 is arranged in such a way, that it is in the path of the movable gauge member 238. The operator places a gauge block 240 of a certain size according to the table given to him on the support 250, and the position of the cam 214, in which the cam is to be set, is determined by an abutment of the movable gauge member 238 against the gauge block 240. As will be readily understood, the cam may be set in a different position on the shaft, when a gauge block of different size is used. If, for example, a gauge block of smaller size is used as indicated by dash lines in Fig. 5, the cam will be in a different position relative to the shaft, when the movable gauge member 238 hits such a smaller gauge block.

The drawings illustrate various embodiments of cam position indicators for use in conjunction with a knitting machine having cams with engaging means by way of example only. It is understood, that the movable and stationary gauge members of the cam position indicators according to the invention may be of different construction. For example, the stationary gauge member may have a support for a connection with the floor rather than for a connection with a stationary or fixed part of the knitting machine. Furthermore, the engaging means of the cams or the like may be arranged at any other place of the cam than at the side surface thereof as shown in the drawings; of course, wherever the engaging means are arranged, they must be in a predetermined position relative to the contour of the cam. Moreover, engaging means of different shape and number may be arranged on the cams or the like instead of the spaced engaging holes shown in the drawings. For example a single engaging hole of polygonal cross-section could be arranged on the cams for holding the movable gauge member having a complementary engaging pin in a predetermined position relative to the contour of the cam. Of course the number, shape, and arrangement of the complementary engaging means on the movable gauge member corresponds to that of the engaging means on the cams or the like. Moreover, it is understood, that the invention is not limited to a warp knitting machine, diagrammatically shown in Fig. 1, that, however, the invention may be applied to any other type of knitting machines.

As will be apparent from above, the invention overcomes the difficulties hitherto encountered in the operation of knitting machines, as the invention renders possible a perfectly timed co-operation of the various intricate mechanisms of a knitting machine by an accurate setting of the cams or the like. Furthermore, the invention permits a checking of the operation of a knitting machine by reading off the value indicated by the gauge members of the cam position indicator attached to a cam for a determination of the set position of such a cam.

Fig. 6 explains a method for the manufacture of a cam or the like for a knitting machine according to the invention, the cams of which are provided with spaced engaging holes for temporary connection with a cam position indicator. Fig. 6 illustrates in full lines a partly finished blank 14' to be used for the manufacture of a cam, for example the cam 14s shown in Fig. 2. The blank 14' has a center bore 15. During the manufacture of the cam two holes 32 are drilled into a side surface of the blank in a predetermined accurate relation to the center 17 of the bore 15. Thereupon, the blank is milled by lo-

cating from said holes 32, so that the contour, shown in dash and dot lines of the cam 14s has a definite relation to the holes 32. Consequently, the spaced holes 32 are in a predetermined position, relative to the center 17 and to the contour of the finished cam 14s. Said holes 32 are the engaging holes for engagement with the engaging pins of the movable gauge member of the cam position indicator as described above.

I have described preferred embodiments of my invention, but it is understood, that numerous changes and omissions may be made without departing from the spirit of my invention.

What I claim is:

1. A knitting machine with cams or the like for temporary connection with the movable gauge member of a cam position indicator, comprising: at least one cam shaft, a plurality of cams for the actuation of various mechanisms of the knitting machine, said cams being adjustably mounted on said shaft for the timing of the operations of said mechanisms relative to each other, and at least one engaging means arranged on each cam at a point from which the contour of the cam is located during the manufacture thereof whereby said engaging means is arranged in a predetermined position relative to the contour of the cam for a temporary positive coupling of the movable gauge member of the cam position indicator with the cam in a predetermined position relative to the contour of the cam.

2. A knitting machine with cams or the like for temporary connection with the movable gauge member of a cam position indicator, comprising: at least one cam shaft, a plurality of cams for the actuation of various mechanisms of the knitting machine, said cams being adjustably mounted on said cam shaft for the timing of the operations of said mechanisms relative to each other, and at least one engaging means arranged on a side surface of each cam at a point from which the contour of the cam is located during the manufacture thereof whereby said engaging means is arranged in a predetermined position relative to the contour of the cam for a temporary positive coupling of the movable gauge member of the cam position indicator with the cam in a predetermined position relative to the contour of the cam.

3. In a knitting machine as claimed in claim 2, each adjustable cam having spaced engaging holes on the side surface from which the contour of the cam is located during the manufacture thereof whereby said engaging holes are arranged in a predetermined position relative to the contour of the cam.

4. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge member, complementary engaging means arranged on said movable gauge member for a temporary positive coupling with engaging means on a cam so as to hold said movable gauge member in a predetermined position relative to the contour of the cam, and supporting means associated with said stationary gauge member for a temporary holding thereof in a predetermined

position relative to said shaft for cooperation with said movable gauge member.

5. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge member, complementary engaging means arranged on said movable gauge member for a temporary positive coupling with engaging means on a cam so as to hold said movable gauge member in a predetermined position relative to the contour of the cam, the portion of the movable gauge member carrying said complementary engaging means being of a shape rendering possible for an attachment of the movable gauge member to any of said plurality of cams a movement of said movable gauge member in a direction at an angle to the longitudinal axis of the shaft carrying such a cam, and supporting means associated with said stationary gauge member for a temporary holding thereof in a predetermined position relative to said shaft for cooperation with said movable gauge member.

6. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge member, complementary engaging means arranged on said movable gauge member for a temporary positive coupling with engaging means on a cam so as to hold said movable gauge member in a predetermined position relative to the contour of the cam, said movable gauge member being made of a substantially flat piece of material, and supporting means associated with said stationary gauge member for a temporary holding thereof in a predetermined position relative to said shaft for cooperation with said movable gauge member.

7. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge member, complementary engaging means arranged on said movable gauge member for a temporary positive coupling with engaging means on a cam so as to hold said movable gauge member in a predetermined position relative to the contour of the cam, the portion of the movable gauge member carrying said complementary engaging means being flat and being of a shape rendering possible for an attachment of the movable gauge member to any of said plurality of cams a movement of said movable gauge member in a direction at an angle to the longitudinal axis of the shaft carrying such a cam, and supporting means associated with said stationary gauge member

for a temporary holding thereof in a predetermined position relative to said shaft for cooperation with said movable gauge member.

8. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on a side surface of each cam in a predetermined position relative to the contour of the cam, a cam position indicator including a movable gauge member and a stationary gauge member, complementary engaging means arranged on said movable gauge member for a temporary positive coupling with engaging means on the side surface of a cam so as to hold said movable gauge member in a predetermined position relative to the contour of the cam, and supporting means associated with said stationary gauge member for a temporary holding thereof in a predetermined position relative to said shaft for cooperation with said movable gauge member.

9. The combination of a knitting machine having at least one cam shaft, a plurality of cams for the actuation of various mechanisms of the knitting machine, said cams being adjustably mounted on said cam shaft for the timing of the operations of said mechanisms relative to each other, each cam having spaced engaging holes on a side surface in a predetermined position relative to the contour of the cam position indicator including a movable gauge member and a stationary gauge member, complementary spaced engaging pins arranged on said movable gauge member for a temporary positive coupling with spaced engaging holes on the side surface of a cam so as to hold said movable gauge member in a predetermined position relative to the contour of the cam, and supporting means associated with said stationary gauge member for a temporary holding thereof in a predetermined position relative to said shaft for cooperation with said movable gauge member.

10. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge member, complementary engaging means arranged on said movable gauge member for a temporary positive coupling with engaging means on a cam so as to hold said movable gauge member in a predetermined position relative to the contour of the cam, supporting means associated with said stationary gauge member for a temporary holding thereof in a predetermined position relative to said shaft for cooperation with said movable gauge member, said stationary gauge member being adjustably mounted on said supporting means, and holding means for holding said stationary gauge member in an adjusted position.

11. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge member, complementary spaced engaging pins arranged on said movable gauge member for a temporary positive coupling with spaced engaging holes on the side surface of a cam so as to hold said movable gauge member in a predetermined position relative to the contour of the cam, and supporting means associated with said stationary gauge member for a temporary holding thereof in a predetermined position relative to said shaft for cooperation with said movable gauge member.

each other, engaging means arranged on each cam in a predetermined position relative to the contour of the cam, a cam position indicator including a movable gauge member and a stationary gauge member, complementary engaging means arranged on said movable gauge member for a temporary positive coupling with engaging means on a cam so as to hold said movable gauge member in a predetermined position relative to the contour of the cam, supporting means carrying said stationary gauge member, and clamping means arranged on said supporting means for a temporary connection thereof with a fixed part of the knitting machine so as to hold the stationary gauge member in a predetermined position relative to said shaft for cooperation with said movable gauge member.

12. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge member, complementary engaging means arranged on said movable gauge member for a temporary positive coupling with engaging means on a cam so as to hold said movable gauge member in a predetermined position relative to the contour of the cam, and supporting means carrying said stationary gauge member, a portion of said supporting means being shaped for a temporary engagement with said shaft, and another portion of said supporting means being shaped for engagement with a fixed part of the knitting machine so as to hold the stationary gauge member in a predetermined position relative to said shaft for cooperation with said movable gauge member.

13. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge member, a first indicating means arranged on said movable gauge member, a second indicating means arranged on said stationary gauge member, complementary engaging means arranged on said movable gauge member for a temporary positive coupling with engaging means on a cam so as to hold said movable gauge member in a predetermined position relative to the contour of the cam, and supporting means associated with said stationary gauge member for a temporary holding thereof in a predetermined position relative to said shaft for cooperation of said second indicating means with said first indicating means.

14. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge

member, a graduated scale arranged on said movable gauge member, a pointer arranged on said stationary gauge member, complementary engaging means arranged on said movable gauge member for a temporary positive coupling with engaging means on a cam so as to hold said movable gauge member in a predetermined position relative to the contour of the cam, and supporting means associated with said stationary gauge member for a temporary holding thereof in a predetermined position relative to said shaft for cooperation of said pointer with said graduated scale.

15. The combination of a knitting machine having at least one cam shaft, a plurality of cams for the actuation of various mechanisms of the knitting machine, said cams being adjustably mounted on said cam shaft for the timing of the operations of said mechanisms relative to each other, each cam having spaced engaging holes on a side surface in a predetermined position relative to the contour of the cam, a cam position indicator including a movable gauge member and a stationary gauge member, said movable gauge member being made of a substantially flat piece of material, a graduated scale arranged on said movable gauge member, a pointer arranged on said stationary gauge member, complementary engaging means arranged on said movable gauge member for a temporary positive coupling with engaging means on the side surface of a cam so as to hold said movable gauge member in a predetermined position relative to the contour of the cam, and supporting means associated with said stationary gauge member for a temporary holding thereof in a predetermined position relative to said shaft for cooperation of said pointer with said graduated scale.

16. The combination of a knitting machine having at least one cam shaft, a plurality of cams for the actuation of various mechanisms of the knitting machine, said cams being adjustably mounted on said cam shaft for the timing of the operations of said mechanisms relative to each other, engaging means arranged on each cam in a predetermined position relative to the contour of the cam, a cam position indicator including a movable gauge member and a stationary gauge member, one of said gauge members including a gauge block exchangeably mounted thereon, complementary engaging means arranged on said movable gauge member for a temporary positive coupling with engaging means on a cam so as to hold said movable gauge member in a predetermined position relative to the contour of the cam, and supporting means associated with said stationary gauge member for a temporary holding thereof in a predetermined position relative to said shaft for abutting cooperation with said movable gauge member.

17. A cam position indicator for temporary connection with a cam or the like of a knitting machine, wherein several cams or the like provided with engaging means in a predetermined position relative to their contour are adjustably mounted on at least one shaft for actuation of various mechanisms in timed relationship relative to each other, said cam position indicator comprising: a stationary gauge member, a movable gauge member, complementary engaging means arranged on said movable gauge member for temporary positive coupling with engaging means on a cam so as to hold said movable gauge member in a predetermined position relative to the contour of the cam, the portion of said movable

gauge member carrying said complementary engaging means being of a shape rendering possible for an attachment of the movable gauge member to any of said plurality of cams a movement of said movable gauge member in a direction at an angle to the longitudinal axis of the shaft carrying such a cam, and supporting means associated with said stationary gauge member for a temporary holding thereof in a predetermined position relative to the shaft of the knitting machine for cooperation with said movable gauge member.

18. In a cam position indicator for temporary connection with a cam or the like of a knitting machine as claimed in claim 17, said movable gauge member being made of a substantially flat piece of material.

19. In a cam position indicator for temporary connection with a cam or the like of a knitting machine, wherein several cams or the like are provided with spaced engaging holes on their side surfaces in a predetermined position relative to their contour as claimed in claim 17, said complementary engaging means on the movable gauge member being in the shape of spaced engaging pins.

20. In a cam position indicator for temporary connection with a cam or the like of a knitting machine as claimed in claim 17, said stationary gauge member being adjustably mounted on said supporting means, and holding means for holding said stationary gauge member in an adjusted position.

21. In a cam position indicator for temporary connection with a cam or the like of a knitting machine as claimed in claim 17, said supporting means carrying said stationary gauge member, and clamping means arranged on said supporting means for a temporary connection thereof with a fixed part of the knitting machine.

22. In a cam position indicator for temporary connection with a cam or the like of a knitting

machine as claimed in claim 17, said supporting means carrying said stationary gauge member, a portion of said supporting means being shaped for a temporary engagement with the shaft of the knitting machine, and another portion of said supporting means being shaped for engagement with a fixed part of the knitting machine.

23. In combination with a cam position indicator for temporary connection with a cam or the like of a knitting machine as claimed in claim 17, a first indicating means arranged on said movable gauge member, and a second indicating means arranged on said stationary gauge member for cooperation with said first indicating means.

24. In combination with a cam position indicator for temporary connection with a cam or the like of a knitting machine as claimed in claim 17, a graduated scale arranged on one of said gauge members, and a pointer arranged on the other gauge member for cooperation with said graduated scale.

25. In combination with a cam position indicator for temporary connection with a cam or the like of a knitting machine as claimed in claim 17, a gauge block exchangeably mounted on one of said gauge members for abutting cooperation with the other gauge member.

FRITZ LAMBACH.
